UNITED STATES PATENT OFFICE.

CHARLES E. MCPHERSON, OF ALLEGHENY, PENNSYLVANIA, ASSIGNOR,
BY DIRECT AND MESNE ASSIGNMENTS, TO BENJAMIN A. GROAH, OF
PITTSBURG, PENNSYLVANIA.

HEATER.

SPECIFICATION forming part of Letters Patent No. 790,384, dated May 23, 1905.

Application filed November 10, 1903. Renewed October 27, 1904. Serial No. 230,263.

To all whom it may concern:

Be it known that I, CHARLES E. MCPHERSON, a citizen of the United States of America, residing at Allegheny, in the county of Allegheny and State of Pennsylvania, have invented 5 certain new and useful Improvements in Heaters, of which the following is a specification, reference being had therein to the accompanying drawings.

10 This invention relates to certain new and useful improvements in heaters, more especially to that class in which gas is employed as a fuel; and the invention has for its object the provision of a heater adapted to receive 15 its fuel from a gas-jet extended into the same, and which may be advantageously used for the heating of halls or rooms by the disposal of the heater below the floor of the room or hallway to be heated.

20 Briefly described, the invention comprises an outer and an inner shell or casing, the inner shell or casing suitably supported in the outer one and having a closed upper end which carries a heating-coil, preferably in the form 25 of a spiral cone. The outer casing is suspended from a box that is supported from the floor and is covered with a radiator-covering of the usual type or form of construction. A gas-jet is extended through the outer casing and 30 feeds into the lower end of the inner casing, and means may be provided whereby the controlling valve or cock of the gas-supply line may be operated from above the heater. Means 35 is also provided for protecting the floor from the heat thrown off by the heater.

All of the above construction, together with other details entering into my invention, will be hereinafter more specifically described and then particularly pointed out in the claims, 40 and in describing the invention in detail reference will be had to the accompanying drawings, forming a part of this application, and wherein like numerals of reference will be employed for designating like parts throughout the different views, in which—

Figure 1 is a side elevation of my improved heater, showing a portion of the floor in sec-

tion. Fig. 2 is a central vertical sectional view. Fig. 3 is a top plan view with the radiator covering or grating removed. Fig. 4 50 is a top plan view with the radiator covering or grating and the top of the inner shell and the heating-coil removed. Fig. 5 is a top plan view of the floor-plate and radiator covering or grating. Fig. 6 is a detached detail side 55 elevation of the heating-coil. Fig. 7 is a perspective view illustrating how the controlling valve or cock in the gas-supply line may be operated from above the heater.

To put my invention into practice, I provide 60 an outer casing or shell 1, generally made cylindrical, though not necessarily so, and an inner shell 2, conforming in contour to the outer shell 1. The shell 1 at its upper end extends into a substantially rectangular 65 box or frame 3, the side walls of which are turned over at their upper edges to form a flange 4, which rests upon the shoulder provided therefor in the rectangular floor-plate 5, which floor-plate is also recessed or shoudered to receive the radiator covering or grating 6, which may be of the ordinary form, 70 having a shut-off or dampers so arranged as to be turned to permit the heat to escape into the room or shut off the heat from the room 75 in the manner well known. I preferably surround the box 3 with an asbestos covering 7, whereby to protect the adjacent wood from the heat. The inner shell or casing 2 is preferably of less length than the outer shell or 80 casing 1 and is suitably supported therein, as by angle-brackets 8, this inner shell or casing being provided with one or more openings 9 near the upper end to permit the escape of the combustibles. On the upper end of the 85 inner shell or casing 2 is fitted a cap or cover 10, and this cap or cover has secured thereto a heating-coil 11, which in practice I have generally made of copper rod wound in spiral cone form, the apex of the cone being downward and lying at a point directly above the mixer and burner 12, carried on the gas-supply line 14, which supply-line extends through an opening 15 provided therefor in the outer

shell or casing 1. The supply-line 14 is beneath the lower end of the inner shell or casing 2, with the mixer and burner 12 projecting up into said casing; but in order to protect the inner casing from the direct action of the flames I provide same with an interior covering 16 of asbestos or other heat-resisting material. As the heater is generally located below the room or hallway which it is desired to heat, it is preferable to provide means whereby the same may be operated from above the heater, and to this end I attach to the stem of the valve 17 of the supply-pipe 14 a rod 18, adapted to project up into the floor 19, whereby to be engaged and operated by the key 20 of suitable form. When so operated, the controlling-valve 17 will be so arranged that when turned to close the same the valve will not be entirely seated, permitting sufficient gas to pass through to burn as a pilot-light in the mixer and burner 12. The provision of a heating-coil 11 enables me to obtain a considerably greater amount of heat than would be possible were the heating of the shells or casings alone accomplished, this copper coil throwing off its heat, which passes upwardly through the radiator covering or grating. The provision of the asbestos covering around the box 3 prevents any danger of the wood adjacent to the box becoming overheated. The bottom of the box 3 is generally provided with one or more apertures 21. The gas-supply 14 is provided with a combined mixer and burner-top 12 on its end, the mixer being so constructed as to effect a perfect mixing of the air and gas prior to its reaching the point of ignition to assist in effecting perfect combustion, which is rendered complete by the heat-producing coil 11 eliminating all fumes, so that only the heated air passes up through radiator 6. In Fig. 1 I show at 22 how connection may be made with the box 3 and a flue (not shown) should this be desired in any particular case.

While I have herein shown and described a practical embodiment of my invention as it is practiced by me, it will be noted that various changes may be made in the details of con-

struction without departing from the spirit thereof.

Having fully described my invention, what I claim as new, and desire to secure by Letters Patent, is—

1. In a heater of the type described, a box or frame suitably supported, an outer shell or casing fitted in said box or frame, an inner shell or casing supported by the outer shell or casing, a lid or cover for said inner shell, a heating-coil carried by said lid or cover, and a fuel-supply communicating with the lower end of the inner shell, substantially as described. 55

2. In a heater of the type set forth, an open-ended casing and a removable cover for closing one end of the casing carrying a heating-coil, extending adjacent the opposite open end of the casing. 65

3. In a heater of the type set forth, a casing having its ends open, a removable closure for one end of said casing carrying a heating-coil extending adjacent the opposite casing end, and a heat-resisting material in the casing below said coil. 70

4. In a heater of the type set forth a pair of open-ended casings located one within the other, a heating-coil supported from the top of the inner casing, and a fuel-supply leading into the bottom of said inner casing. 75

5. In a heater of the type set forth, an open-ended casing and a removable cover for closing one end of the casing, carrying a heating device, extending adjacent the opposite end of the casing; substantially as described. 80

6. In a heater of the type set forth, an open-ended casing and a removable cover for closing one end of the casing, carrying a heating device, extending adjacent the opposite end of the casing, and a refractory lining in said casing; substantially as described. 85

In testimony whereof I affix my signature in the presence of two witnesses.

CHARLES E. MCPHERSON.
